AIRPLANE MAIL PICKUP

Elmer Clampitt, Indianapolis, Ind., assignor of
one-third to Harry R. Champ, Indianapolis,
Ind.

Application July 1, 1935, Serial No. 29,202

10 Claims. (Cl. 258—1)

This invention relates to means for picking up articles from the ground by flying airplanes. One particular use of the invention is that in picking up sacks of mail at various stations or airports 5 without requiring the airplane to land and take off so that considerable time may be saved in the schedule of the mail carrying plane between terminals.

An important object of my invention is to provide an apparatus to be carried by the plane which will permit the picking up of the stationary article by the plane without imparting a severe shock thereto. A further important object is to provide a device which will permit engagement 15 with the article to be picked up without immediately starting that article into motion corresponding to that of the plane but will automatically compensate for the inertia of the article and then pull the article in toward the plane as the plane progresses.

A still further important object of my invention is to provide an article engaging device which may normally be swung into such a position as will not interfere with landing and as also will not 25 set up wind resistance, but at the same time may be brought around into that position whereby an article engaging hook may be attached thereto by an operator in the plane. A further important object of my invention is to provide a 30 very simple and relatively light mechanism for accomplishing the above indicated objects, including a mast for carrying the article to be picked up having certain advantages, namely that of permitting easy and quick mounting of the article thereon and for cooperating with the plane mechanism so as to insure pick up of the article.

Reference is made to the accompanying drawings wherein one particular form of my invention 40 is illustrated, Fig. 1 being a side elevation of the structure embodying my invention;

Fig. 2, a side elevation of a plane carrying my invention;

Fig. 3, a top plane view of the ground tower;

Fig. 4, a front elevation of the tower;

Fig. 5, a detail on an enlarged scale in left hand side elevation of the plane carried mechanism;

Fig. 6, a top plan view of the plane carried mechanism;

Fig. 7, a vertical longitudinal section on the line 7—7 in Fig. 6;

Fig. 8, a detail on a still further enlarged scale in right hand elevation of the plane carried mechanism, and

Fig. 9, a rear elevation thereof.

Like character of reference indicate like parts throughout the several views in the drawings.

Referring first to Figs. 3 and 4 illustrating the ground tower, I provide a base 10 centrally of which is carried a post 11 to extend vertically therefrom for a considerable distance. The post 11 is revolvably carried within a standard 12 and a lever 13 is fixed to the post 11 to have a down-turned leg 14, Fig. 1, which may drop into any one of a plurality of holes 15 placed about the base 10. By lifting the lever 13, the leg 14 is withdrawn from the hole 15 and by pulling the lever 13 around, the post 11 may be correspondingly revolved and secured in any desired position by dropping the lever 13 to carry the leg 14 into the selected hole 15.

On the top end of the post 11 is carried a bow 16, here shown as being substantially circular with the upper portion cut away. The bow is centrally carried to extend above the top end of the post 11 and has a shield 17 secured across its lower portion to cover over from one side the lower portion of the bow and the upper end of the post 11. The shield 17 is preferably curved around at its lower end, Fig. 1, to provide a smooth rounded corner at the lower end of the shield. Preferably a lamp 18 is mounted toward each end of the shield 17, on its forward side so as to project light rays upwardly and inwardly to intersect on an extended axis of the post 11 as indicated in Fig. 4 so that the center of the bow 16 may be indicated by the intersection of the light beams to guide the aviator at night.

From the upper ends of the bow 16, I turn rearwardly and outwardly in each case a wing or guard 19 to have the wings diverging one from the other and be inclined downwardly somewhat from the horizontal. These wings or guards 19 are preferably elastic in nature to some extent or at least will spring some at their junctions with the upper ends of the bow 16.

The article to be picked up, here indicated as a mail bag 20, is provided with a looped carrier 21 in the nature of a cord or cable. At each upper end of the bow 16 is a forwardly directed pin 22 over which pin the cord 21 is hung. Each side of the looped cord 21 is spread to pass around forwardly turned arms 23, one on each side extending from the bow 16. The bag 20 is thus supported merely by its downward pull on these pins. The sack 20 is carried up and placed in the hanging position by an operator who climbs the ladder 24 carried by the post 11, the upper end of the ladder having an extension 25 which may be pushed upwardly to permit engagement with the cord 21 on 50 55

the upper pins 22 and side pins 23 and then be pulled down out of the way.

The cooperating mechanism carried by the plane 26 is mounted preferably on the floor 27 of the plane. A drum 28, Fig. 7, having side plates 29 and 30 is revolvably mounted on an axle 31 between supporting plates 32 and 33. A spring 34 is secured by one end to the axle 31 and by the other end to the drum 28, the spring 34 being confined entirely within the drum. A cable 35 is wound around the drum on its outer side. By means of a crank 36 secured to an outer projecting end of the axle 31, the spring 34 may be wound up to give the desired pull on the drum 28. The cable 35 is so wound around the drum 28 as to pull off rearwardly from the under side of the drum and pass over a roller or bar 37 mounted between the plates 32 and 33.

From the rear end of the plates 32 and 33 is suspended a lever system to hang from the under side of the floor 27 in a rockable manner. An arm 38 is fixed to a bar 39 to have a leg 40 hinged thereto by one end. The arm 38 is preferably provided with a flexible portion 41 in the nature of a flat steel spring so as to permit a yielding motion of the arm 38 laterally of the plane. The bar 39 is revolvably carried between projecting brackets extending from the plates 32 and 33 and a lever 42 is fixed by one end to the bar 39 as a means of rocking the bar. The other end of the lever 42 is interconnected with an operating lever 43 by means of a link 44 so that by swinging the lever 43, the arm 38 may be swung correspondingly.

Rockably mounted on the bar 39 is a lever 45 from the outer end of which pivotally hangs a link 46 to have its lower end pivotally engaging with the leg or foot 40 at a distance removed from the hinged connection of the leg 40 with the arm 38. From the hub of the lever 45 on the bar 39, extends another lever 47 angularly therefrom in the nature of a bell crank. From the outer end of this lever 47 extends a link 48 forwardly to the lower end of a control lever 49, both levers 43 and 49 herein shown as being mounted on the same axle 50.

Normally the arm 38, link 46 and leg 40 are carried in the position as indicated by the dash lines in Figs. 1 and 8 wherein those members are brought around up against the under side of the floor 27 to extend rearwardly thereunder.

A trap door 51 is provided in the floor 27 and by suitable manipulation of the levers 43 and 49, the outer end of the leg 40 is presented 55 through the opening normally closed by the door 51 as indicated by the dot-dash lines in Fig. 8. When the outer end of the leg 40 is thus presented, a hook 52 on the end of the cable 35 is attached to this end of the leg by means of a 60 conical plug 53, preferably made of rubber to give an elastic grip, and is pressed into the end of the leg. The leg 40 is preferably made to have a U-section, Fig. 5, and the plug 53 is pressed between the side members of the leg 40 65 at its outer end as indicated in Fig. 5. The levers 43 and 49 are then suitably manipulated so as to first allow the leg 40 to swing around downwardly with its attached hook 52 and then have the arms 38 and 46 swing slightly rearwardly, all to the solid line positions as indicated in Fig. 8, wherein a length of the cable 35 rests within the leg 40 extending upwardly from the plug 53. Preferably, although not necessarily so, the cable 35 passes between fingers 70 75 54 and 55 carried on the rear side of the link

46 near its hinged connection with the lever 45, the cable being free to be carried rearwardly from between the fingers. The link 46 is preferably provided with a flexible link 56 corresponding to the link 41 of the arm 38 so that 5 both the link and the arm may yield slightly laterally of the plane.

The cable 35 is provided with a knot 57 as a means of preventing the spring 34 from pulling on the cable 35 tending to pull it back around 10 the drum 28, the knot 57 being caught on the rear side of a bar 58 by lifting the cable 35 upwardly thereunder and into a V-notch 59, Fig. 9. Thus the spring 34 may have an initial tension on the cable 35 from the bar 58 but the 15 outer end beyond the notch 57 hangs freely downwardly and behind the members above indicated to have the hook 52 supported by the outer end of the leg 40. It is to be observed that the open end of the hook 52 is turned in the forward direction of the plane.

Now with the hook 52 presented by the leg 40 in the extended position under the floor 27, the plane 26 is brought over the bow 16 to have the hook 52 brought up on as near a center line between the guards 19 as is possible and at an elevation which will cause the hook 52 to engage the upper horizontally disposed length of the cord 21, the hook 52 being permissibly allowed to come below that line since the rear inclination of the leg 40 will cause the cord 21 to relatively slide down into engagement with the hook 52 as the plane proceeds forwardly thereover. Any forward pull on the cord 21 will, of course, cause it to become disengaged from 35 the pins 22 and 23 without any substantial resistance.

Immediately the hook 52 engages the cord 21 and thereby dislodges it from its support by the bow 16, the weight of the bag 20 is then carried 40 by the hook and in turn by the cable 35. This applied weight will cause the cable 35 to be pulled downwardly to slide the knot 57 down from engagement against the rear side of the bar 58 and thus permit the spring 34 to exert its pull 45 on the cable 35. Since there is an evident amount of inertia in the bag 20, the first result is that the cable 35 is actually pulled rearwardly to unwind from the drum 28 as the plane proceeds forwardly, thereby winding up the spring 34 and 50 gradually decelerating the relative rear travel of the sack 20 until such a balance is reached that the bag 20 and the plane 26 move forwardly at the same speeds. When this balance is reached, the spring 34 is of that strength that 55 it will then begin gradually to revolve the drum 28 in the opposite direction to wind the cable 35 therearound until the bag 20 is presented at the opening covered ordinarily by the door 51.

If the tension of the spring is not sufficient to 60 accomplish this result, the axle 31 may be revolved by means of the crank 36 to apply additional tension to the spring and thereby complete the operation of bringing the mail bag up within the plane. The length of the cable 35 65 may range over a considerable length such as from 100 to 300 feet, depending upon several factors, such as the speed of the plane, height of the post 11, and the usual weight of the sack 20. The mail sack will not come back against 70 the plane with increasing velocity but rather the speed of the returning sack will be somewhat slowed down by reason of the outer portion of the spring 34 coming into contact with the inner side of the drum and also the side plates. 75

This may further be regulated by means of the lever 36 being set such that the spring 34 will be sufficiently unwound by the time the sack comes within a few feet of the plane as to just 5 balance the weight of the sack and then further return is accomplished by returning the crank 36 as above indicated.

When the sack reaches that position, it may be grasped by the operator and the cable 35 disengaged whereupon the levers 43 and 49 may then be manipulated from within the plane to carry the leg 40 on around and up against the floor 27 to its normal inoperative position. Of course any lateral deviation from the desired 10 course of the plane 26 in approaching the bow 16, may be compensated to some extent by the leg 40 striking one or the other of the guards 19 so as to guide the hook 52 on up to the upper 15 side of the cord 21 carried therebetween at their forward ends, the leg 40 being permitted to be carried laterally somewhat by the guard 19 as the case may be through the flexible portions 41 and 56 in the arm 38 and the link 46.

While I have herein shown and described my 25 invention in the form as now best known to me, it is obvious that structural changes may be made without departing from the spirit of the invention and I, therefore, do not desire to be limited to that precise form beyond the limitations as may 30 be imposed by the following claims.

I claim:

1. In an airplane article pickup system, a drum carried by the plane, spring means resisting unwinding of the drum, a cable wound about the 25 drum, a foot carried by the airplane to swing downwardly therefrom, a hook on the cable adapted to be carried by the foot at its lower end, and a ground member having an opening across its upper end, an article carrying cord releasably 30 extended across the opening, said hook being hooked under said cord upon flight of the airplane, the inertia of said article initially causing said cable to unwind from said drum and wind said spring, said spring overcoming said inertia 35 pull and then unwinding to wind up the cable and draw the article against wind resistance to the airplane.

2. In an airplane article pickup system, a drum carried by the plane, spring means resisting unwinding of the drum, a cable wound about the 40 drum, a foot carried by the airplane to swing downwardly therefrom, a hook on the cable adapted to be carried by the foot at its lower end, and a ground member having an opening across its upper end, an article carrying cord releasably 45 extended across the opening, said hook being hooked under said cord upon flight of the airplane, the inertia of said article initially causing said cable to unwind from said drum and wind said spring, said spring overcoming said inertia 50 pull and then unwinding to wind up the cable and draw the article against wind resistance to the airplane, said cable being initially carried to have a substantial part thereof wound on said drum, with the spring substantially unwound.

3. In an airplane article pickup system, a drum carried by the plane, spring means resisting unwinding of the drum, a cable wound about the 55 drum, a leg carried by the airplane to swing downwardly therefrom, a hook on the cable adapted to be carried by the leg at its lower end, and a ground member having an opening across its upper end, an article carrying cord releasably 60 extended across the opening, said hook being hooked under said cord upon flight of the airplane, the

inertia of said article initially causing said cable to unwind from said drum and wind said spring, said spring overcoming said inertia pull and then unwinding to wind up the cable and draw the article against wind resistance to the airplane, 65 said cable being initially carried to have a substantial part thereof wound on said drum, with the spring substantially unwound, and means releasably holding the outer end of the cable extending to said leg end to be without initial pull 70 from said spring, said means being rendered inoperative upon pull on said hook.

4. In an airplane article pickup system, a drum carried by the plane, spring means resisting unwinding of the drum, a cable wound about the 75 drum, a foot carried by the airplane to swing downwardly therefrom, a hook on the cable adapted to be carried by the foot at its lower end, and a ground member having an opening across its upper end, an article carrying cord releasably 80 extended across the opening, said hook being hooked under said cord upon flight of the airplane, the inertia of said article initially causing said cable to unwind from said drum and wind said spring, said spring overcoming said inertia pull 85 and then unwinding to wind up the cable and draw the article against wind resistance to the airplane, and means for varying the degree of rewinding of the cable.

5. In an airplane article pickup mechanism, a 90 revoluble drum carried by the airplane, a cable wound about the drum, a spring normally tending to turn the drum to wind up said cable, a leg swingably carried by the airplane, a hook on said cable and means releasably attaching the hook 95 to said leg, said cable initially being substantially entirely wound on the drum with the spring substantially unwound.

6. In an airplane article pickup mechanism, a 100 revoluble drum carried by the airplane, a cable wound about the drum, a spring normally tending to turn the drum to wind up said cable, a leg swingably carried by the airplane, a hook on said cable and means releasably attaching the hook to said leg, said cable initially being substantially 105 entirely wound on the drum with the spring substantially unwound, a knot on the cable determining its wound position, and a notched member above the path of the unwinding cable where- 110 by said cable may be lifted into the notch of the 115 member to have said knot strike thereagainst and limit winding of the cable, said cable being pulled from said notch by pull of an article engaged by said hook.

7. In an airplane article pickup mechanism, a 120 cable carried by the airplane, an article engaging member fixed to the cable, an arm rockably carried to swing downwardly from the airplane, a foot hinged to the arm to hang therefrom, a link hinged to the foot at a distance from its hinge 125 connection with said arm, a lever engaging the upper end of said link, and an operating lever interconnected with the upper end of said arm, said link engaging lever serving to swing said foot on said arm and said operating lever serv- 130 ing to swing both the arm and foot in unison whereby the arm and foot may be swung in ex- 135 tended relation back under the airplane, or the foot folded up to have its lower end presented adjacent the upper end of the arm, and means 140 releasably interconnecting said article engaging member with said foot lower end.

8. In an airplane article pickup mechanism, a 145 cable carried by the airplane, an article engaging member fixed to the cable, an arm rockably car- 150

- ried to swing downwardly from the airplane, a foot hinged to the arm to hang therefrom, a link hinged to the foot at a distance from its hinge connection with said arm, a lever engaging the upper end of said link, and an operating lever interconnected with the upper end of said arm, said link engaging lever serving to swing said foot on said arm and said operating lever serving to swing both the arm and foot in unison whereby the arm and foot may be swung in extended relation back under the airplane, or the foot folded up to have its lower end presented adjacent the upper end of the arm, and means releasably interconnecting said article engaging member with said foot lower end, said arm and said link having portions thereof flexible laterally of the airplane.
9. In an airplane article pickup system, means carried by the airplane to engage an article, and ground means for presenting the article comprising a post, an upturned bow on the upper ends of the post, a looped cord for carrying an article,

and a pin at each upturned end of said bow across which pins said loop is hung to depend therefrom, and a guide arm extending rearwardly from each of said bow ends and diverging one from the other, and a transverse shield across the lower portion of said bow in front of which said article may hang from said cord.

10. In an airplane article pickup system, means carried by the airplane to engage an article, and ground means for presenting the article comprising a post, an upturned bow on the upper end of the post, a looped cord for carrying an article, and a pin at each upturned end of said bow across which pins said loop is hung to depend therefrom, and a guide arm extending rearwardly from each of said bow ends and diverging one from the other, and a transverse shield across the lower portion of said bow in front of which said article may hang from said cord, and means revolvably positioning said bow in selected positions. 20

ELMER CLAMPITT.
